UNITED STATES PATENT OFFICE.

HENRY PRICE, OF KENTON, OHIO.

DESIGN FOR A BADGE OR JEWELRY.

SPECIFICATION forming part of Design No. 17,054, dated January 4, 1887.

Application filed November 27, 1886. Serial No. 220,099. Term of patent 7 years.

To all whom it may concern:

Be it known that I, HENRY PRICE, a citizen of the United States, residing at Kenton, in the county of Hardin and State of Ohio, have 5 invented and produced a new and original Design for Jewelry and Badges, of which the following is a specification, reference being had to the accompanying drawings, forming part thereof.

10 In the accompanying drawings, Figure 1 illustrates a scarf-pin with my design. Fig. 2 shows a badge, and Fig. 3 a watch-charm, and Fig. 4 a pin, with the design thereon.

15 The leading feature of my design consists in a base having upon its outer surface the conventionalized configuration of a crank.

In the several figures of the drawings, B represents the base, and A the representation of a crank.

20 In Fig. 1 the base B is the ornamental head

of a scarf-pin. In Fig. 2 the base forms a portion of a badge. Fig. 3 represents the design on the surface of a watch-charm; and Fig. 4 represents the design on a pin, which latter forms the base.

Having fully described my design, what I claim as new, and desire to secure by Letters Patent, is—

The design for badges or jewelry herein shown and described, the same consisting of 30 a base having upon its outer surface the conventionalized configuration of a crank.

In testimony whereof I have signed this specification in the presence of two subscribing witnesses.

HENRY PRICE.
